UNITED STATES PATENT OFFICE

2,572,048

TOBACCO PIPE

Alexander Gordon Nisbet, Rye, N. Y.

Application March 31, 1945, Serial No. 585,843

4 Claims. (Cl. 131—203)

1

My invention relates to improvements in pipes employed for smoking.

In pipes of the types heretofore manufactured in which the pipe stem is tapped directly into the pipe bowl or combustion chamber, it has been found that condensate from the combustion chamber and saliva from the mouth, transmitted through the pipe stem, often collected at the bottom of the combustion chamber. As a result of this the lower one-fourth of the tobacco in the bowl tended to become saturated with moisture and would not burn, making it unnecessarily wasteful because this quantity from each bowlful had to be thrown away. It was also found that this wet tobacco had a tendency to sour the pipe thereby greatly lessening the smoker's enjoyment.

It is therefore one of the principal objects of my invention to provide a novel and improved pipe construction by means of which the above described disadvantages will be overcome and which will afford an economical, sweet, dry and pleasurable smoke to the user.

Other objects of my invention will become apparent from the description to follow or will hereinafter be pointed out.

In the accompanying drawings,

Fig. 1 is a longitudinal sectional view of a pipe constructed and arranged in accordance with my invention;

Fig. 2 is a cross-sectional view taken substantially along the line 2—2 of Fig. 1;

Fig. 3 is a cross-sectional view taken substantially along the line 3—3 of Fig. 1; and

Fig. 4 is an end elevational view of the pipe shown in Fig. 1.

Referring now in detail to the drawings I have shown a tobacco pipe constructed and arranged in accordance with my invention and consisting generally of a bowl or combustion chamber 10 for receiving a supply of tobacco therein, a stem 20 and a mouth piece 30. The bowl 10 may be provided with a reduced shank portion 11 at the bottom thereof which is externally threaded and which is adapted to be screwed into a correspondingly threaded opening 21 in the stem 20. The mouth piece 30 is provided, at its inner end, with a reduced shank portion 31 which is frictionally received in the longitudinal bore or opening 22 of the stem. It is thus seen that the assembly and disassembly of the main parts of the pipe are relatively simple and may be quickly accomplished.

It is noted that the stem 20 is provided with a circular portion 20a disposed below the bowl

2

10 and which may correspond in contour to that of the said bowl 10 and that the bore 22 of the stem 20 also extends underneath the said bowl 10, to form a collecting chamber 23 for the condensate from the bowl 10. A through aperture 12 in the bottom wall of the bowl 10 is provided which communicates with the collecting chamber 23.

To prevent the condensate or moisture in the 10 collecting chamber 23 from entering the bore 22, I provide an absorbent pad 24 resting at the bottom of the said collecting chamber to hold the moisture which might flow from the bowl 10.

In accordance with my invention I provide a 15 condensate diffuser 14 designed to lead the flow of condensate from the bowl 10 to the absorbent pad 24 in the collecting chamber 23. The said diffuser 14 which may be of metallic or other suitable material comprises an upper tubular portion 15 frictionally received in the aperture 12 of the bowl 10, and outwardly flared finger portions 16 depending therefrom. The diffuser 14 is so designed that the fingers 16 will contactively engage the pad 24 to thereby retain the same in position and to form a passageway for the condensate from the bowl to the pad 24, at the same time breaking up capillary action which might cause this moisture to build up and back into the combustion chamber to wet the tobacco therein.

The mouthpiece 30 is provided with a longitudinal axial bore 31 communicating at the inner end with the bore 22 of the stem 20 and terminating at its outer end in an outwardly flared and flattened portion 32. In accordance with my invention I design the bores 31 and 32 in such manner that the top wall of the portion 32 is tangent to and forms a continuation of the top portion of the wall of the bore 31, while the depth of the flattened bore portion 32 is approximately one-half of the diameter of the bore 31, as clearly shown in Figs. 1 and 4 of the drawings.

It is thus seen from the above described construction that the bore 22 of the pipe stem, which is relatively large, communicates directly with the collecting chamber 23 thus permitting saliva which enters the bore 22 from the mouth piece 30, to flow directly to the collecting chamber and to the pad 24 therein. The bore 22 is preferably made relatively large so that it will break up any tendency of capillary action to retard the said saliva in its passage to the collecting chamber.

To facilitate the discharge of saliva from the

mouth piece 30 into the bore 22 I provide a saliva diffuser 35 which may be made of metal or other suitable material and which comprises a tubular member having a portion thereof frictionally received in the bore 31, and a portion projecting into the bore 22. The said last named projecting portion of the diffuser 35 terminates in a downwardly flared finger portion 35a, the extreme tip of which is preferably spaced from the wall surrounding the bore 22 to break up any possibility of capillary flow of saliva or the condensate from the bore 22 back into the bore 31 of the mouth piece.

To insure that only a minimum of moisture can collect in the mouth piece it is contemplated, under my novel pipe construction as above described to make my mouth piece of minimum length compatible with bite and structural requirements.

The collecting chamber is so designed as to provide an ample moisture reservoir and trap to which ready access can be had by unscrewing the bowl for draining, cleaning and replacement of the pad 24.

It will thus be seen that there is provided a device in which the objects of my invention are achieved, and which is well adapted to meet the conditions of practical use.

As various possible embodiments might be made of the above invention, and as various changes might be made in the embodiments above set forth, it is understood that all matter herein set forth or shown in the accompanying drawing is to be interpreted as illustrative and not in a limiting sense.

Having described my invention, what I claim and desire to secure by Letters Patent is:

1. In a tobacco pipe comprising a bowl having an aperture therein permitting smoke to be drawn downwardly therethrough, in combination; a stem of relatively large bore detachably secured to the lower portion of the bowl, said stem being enlarged to provide an internal portion having a bottom surface of relatively large area disposed beneath said aperture; an absorbent pad having upper and lower surfaces, said lower surface being

in engagement with said surface of large area; and an outwardly flaring diffusing member having lateral apertures therein and having its smaller portion in communication with said aperture and its larger portion in engagement with said upper surface of said pad to hold the outer portions of said pad against said surface of large area.

5 2. A tobacco pipe as in claim 1 in which the outwardly flaring portion of the diffusing member is frustro-conical in shape.

3. A tobacco pipe as in claim 1 in which the lateral apertures consist of notches in the lower periphery of the diffusing member.

15 4. A tobacco pipe as in claim 1 in which the surface of large area is flat and is coplanar with the bottom of said bore, whereby, when the bore is downwardly inclined, moisture in said bore will run downwardly and be absorbed by a lateral portion of said pad.

20 A. GORDON NISBET.
